TELEGRAPH SYSTEM

Hendrik C. A. van Duuren, Wassenaar, Netherlands, assignor to Kingdom of the Netherlands, Post Office Administration, The Hague, Netherlands

Application September 24, 1938, Serial No. 231,479
In the Netherlands September 25, 1937

30 Claims. (Cl. 250—8)

The present invention relates to telegraph systems, particularly of the type-printing class. The invention is primarily concerned with the troubles arising in these systems from transmission disturbances. Transmission disturbances are particularly present in radio transmission, where static and fading frequently mutilate the signals. For this reason, the invention has its primary field of utility in connection with radio transmission, but it will be understood that the invention can also be employed in wire transmission systems over land and cable lines for avoiding difficulties arising from atmospheric disturbances, induction from adjacent power lines, etc.

British Patent No. 419,526, issued to Arjen Bakker and myself, illustrates one type of telegraph system which has been developed to cope with the problem of atmospheric disturbances in radio transmission. The system of this patent operates upon the theory of utilizing two carrier waves of different frequencies in each one-way path of communication. One signal element, which may be termed the marking element, is imposed on one carrier wave, and the other signal element, which may be termed the spacing element, is imposed on the other carrier wave. The theory underlying this mode of operation is that so long as both signal elements on the two waves arrive undisturbed at the receiving station, the latter will continue its printing operation, but if one of the signal elements is mutilated by a parasitic impulse or by fading, the receiver will be stopped automatically and means put into operation for obtaining the emission of a non-mutilated signal from the transmitting station. This prior type of system requires the use of four transmission channels, two for the signal elements of the message and two for the corrective or controlling signal elements which are adapted to be transmitted back from the receiving station to the transmitting station.

The present invention, on the other hand, only requires two transmission channels for the same purposes. In other words, the present invention provides a system in which the mutually protected elements are emitted one after the other on a single channel. The signal elements are made mutually protective by having them comprise impulses having different electrical values which are so chosen as to produce a constant ratio or constant total electrical value for each transmitted signal. Any deviation from this constant relationship in the signals received at the receiving station is an indication that the

signal has been mutilated, calling for a retransmission of that signal. For example, if the signals emitted on the single wave are thought to consist, in the manner of Baudot code, of a given number of negative and positive signal elements, which are transmitted in a combination characteristic of each signal, then the protection of the signal is obtained according to the invention by causing the proportion of positive and negative elements to be identical in each signal. The occurrence of a parasitic impulse or of fading during the transmission of the signal is detected through the deviation from normal of the proportion of positive and negative elements as determined at the receiver.

If it were attempted to employ the normal five unit code, represented by the Baudot code, in the application of the above idea, a shortage of different combinations would result, because when operating upon the basis of a given proportion or ratio of positive and negative elements there would be several combinations of such five unit code which obviously could not satisfy the requirements relating to this proportion or ratio. It is therefore desirable to employ a code in which the signals are made up of a greater number than five units or elements.

In the preferred embodiment of my invention herein disclosed I employ a code containing eight units or elements. The eight unit code is particularly suitable for the practice of the present invention in that when the code is obtained by conversion from the five unit code which is usually employed in mechanical telegraphs or land lines, thirty of the thirty-two combinations of the five unit code may be changed into eight unit code signals by simply adding three elements, of which three, two, one, or none are marking units. Only those signals of the five unit code which have five identical units have to be transformed in a different manner.

In the system of the aforementioned British patent, each signal element is protected in and of itself, and hence it is possible to transmit a single element as warning of the reception of a mutilated signal. In the system of the present invention each signal element is not protected in and of itself, but, to the contrary, the protection only applies to every combination of elements constituting a signal. Hence, in this system an entire signal is employed for this purpose. Inasmuch as the eight unit code, when subjected to the condition that each signal shall

comprise four positive and four negative elements, affords seventy distinct signal combinations, it will be evident that a large number of signals will be available for use as warning signals. The invention provides for the repetition of a limited number (e. g., five, depending on the transmission time) of signals whenever a disturbance has been signaled. If the order (from the receiver to the transmitter) requesting such repetition should have no effect, another signal, given after some delay, will thereupon be transmitted, and this will represent an order to repeat a greater number of signals than the first mentioned number. Inasmuch as several warning signals are available in the above described code relation, it will be evident that consecutive warning signals, each time suitably amended or differentiated from preceding warning signals, may repeatedly be given.

The preferred embodiment of the invention as it will be hereinafter described utilizes a transmitter which transmits with an eight unit code, in response to received signals which are formed on the basis of a five unit code. The transmitter includes transforming apparatus for transforming the five unit signals into eight unit signals. Similarly, this embodiment utilizes a receiver which receives the eight unit code, and which receiver includes transforming apparatus which retransforms the received eight unit signals into five unit signals for controlling a printer. It will be clear that this transforming apparatus is not essential to the application of the fundamentals of my invention. For example, in situations where messages originate directly at the transmitting station, or in situations where messages received over a land wire in a five unit code (such as the Baudot code) are printed at the transmitting station and are then manually recast into a code having a different number of units, there is no necessity of employing such transforming apparatus. However in view of the fact that in most instances the large bulk of messages will be conveyed over land lines to the radio transmitting station, and in view of the fact that these land lines are usually equipped to work with a five unit code, it is desirable to provide the aforesaid transforming apparatus to transform the five unit code into the eight unit code at the transmitting station, and to transform the eight unit code back into the five unit code at the receiving station. In this regard, it is to be understood that the description of an eight unit system is not to be interpreted as a limitation of the invention, since seven units suffice for obtaining the required number of combinations; provided that in each signal four and three equal signal elements should always occur, in which case seven units provide

1-2-3-4-5-6-7
(1-2-3)(1-2-3-4) -35 combinations

However, the use of eight units is more advantageous since it appears to simplify the apparatus considerably, as in this case all signals from the five unit code, except those having five equal elements, may be used in the eight unit code by merely completing these signals to eight unit signals through the addition of three elements.

If a disturbance is signaled at the receiver due to the arrival of an incorrect proportion of positive and negative elements in a signal, a warning has to be given to the transmitter in the manner indicated above. A transmitter in the direction AB will thus have to transmit the five

unit signals ready at A (e. g., perforated in a paper strip) after their transformation into eight unit signals, and moreover warning signals to transmitter B, as required by reason of disturbances on the path BA (i. e., whenever warning signals which have been transmitted back from transmitter B along the path BA have been mutilated in transmission). The receiver B has to transform the eight unit signals arriving on the radio path into five unit signals, which transformation consists in the simple admission of the first five of the elements of the signal as received to a five unit printer, except in the cases in which the original signal contains five equal elements, or where it was a signal for indicating a disturbance on the path BA (i. e., where transmitter B has been required to transmit a warning signal back along the path BA, which warning signal is mutilated in transit, thereby calling for the transmission of a warning signal in the reverse direction from transmitter A along the path AB to receiver B). The particular requirements to be satisfied by the transmitter A and receiver B will be better understood by referring to the accompanying drawings illustrating one preferred embodiment of my invention. In these drawings:

Figure 1 is a circuit diagram of the transmitter apparatus of each station;

Figure 2 is a circuit diagram of the receiver apparatus of each station;

Figure 3 is a chart illustrating different combinations available in the eight unit code;

Figure 4 is a timing diagram of one group of contactors employed in the transmitter;

Figure 5 is a timing diagram of one group of contactors employed in the receiver; and of the start-stop teletype connected thereto, and

Figure 6 is a timing diagram of different contactors employed in the transmitter and in the receiver, grouped according to the shafts by which these contactors are operated.

Referring first to Figure 3 which shows different code combinations in which the eight unit signal is made up, the transmitter A has to satisfy certain requirements with reference to creating these eight unit signals. For example, the five unit signals which are to be transmitted from transmitter A and which have four equal elements at most, have to be completed by the addition of three elements in such a manner that the resulting eight unit signal contains four positive and four negative elements. For accomplishing this relation, four code combinations of the eight possible combinations of the three added elements are required, viz., for the cases in which one, two, three, or four positive elements were present in the original signal. These four combinations have been shown in Figure 3 at the lines I-IV. In this chart, the signal elements denoted by the circles or zeros may, for convenience of reference, be referred to as the spacing elements, and the signal elements denoted by the X marks may be referred to as the marking elements. For example, in the Baudot code the flat tops in the current wave are commonly referred to as marking elements and the valleys are commonly referred to as spacing elements. Correspondingly, in the present disclosure the X marks in Figure 3 may be regarded as the tops or marking elements and the circles as the valleys or spacing elements, this arbitrary designation, however, being solely for convenience of reference. Referring more particularly to these so-called "normal" signals indicated in lines

I-IV, line I illustrates the three signal elements which are added when the original five unit signal contains only one marking element; line II the three signal elements which are added when the original signal contains two marking elements; line III the three signal elements which are added when the original signal contains three marking elements; and line IV the three signal elements which are added when the original signal contains four marking elements.

A further requirement of the transmitter is that if the original five unit signal has five equal elements, such signal must be transformed into a balanced eight unit signal comprising equal numbers of positive and negative elements. There are two instances of such a five unit signal, one in which all five elements are positive (spacing elements O) and the other in which all five elements are negative (marking elements X). These two signals are shown in their transformed state 20 in lines O and V in Figure 3, from which it will be seen that these two transformed signals differ from each other, although the sequence or grouping of the last three elements is the same in both instances. This sequence or order of the last three elements differs, however, from each of the other four sequences or groupings I, II, III, and IV. When the receiver receives either of the two signals O or V it perceives that a transformation has taken place. Because the sequence of the last three elements is the same in both O and V they only exhaust one of the three-element combinations, which, together with the normal signal combinations I, II, III, and IV, exhaust five combinations in all.

Hence, of the eight possible three-element combinations, three yet remain, and these are used at the transmitter for the emission of warning signals under control of signaling relays, these signals being shown respectively in lines VI, VII, and VIII in Figure 3. The receiver thus has the particular requirement to select between (1) normal signals, represented at I-IV in Figure 3; (2) transformed signals indicated at O and V in which the first five elements have to undergo a retransformation opposed to the transformation experienced by these elements at the transmitter; and (3) warning signals indicated at VI-VII in Figure 3. Lastly, the receiver B should be adapted to control its own transmitter B for the emission of warning signals to A whenever a disturbance occurs on the path AB. Similarly, in this same regard, the reception of a warning signal at B has to occasion the repetition of the warning signal previously mutilated on the path BA. The converse of this situation is, of course, true in the event that the message signals are transmitted at B for reception at A.

Referring now to Figure 1, the transmitter comprises the five contact fingers or feeling tongues 21 to 25, inclusive, adapted to coact with the perforated paper tape in which the message is recorded in conventional five unit code. When these contact fingers are in their upper positions (which is the case when the tongue registers with perforations) they establish engagement with cooperating upper contacts, and when they are in their lower positions they establish engagement with cooperating lower contacts. Different polarities or potentials are imposed on these contacts to establish the marking or spacing elements of the first five-unit portion of the complete eight unit signal. The perforated paper tape is intermittently advanced under control of the timing contact 2, which has connection with

negative battery and which governs the energization of the conventional starting magnet S. The other terminal of this starting magnet has connection through ground with battery mid-point. 5 Throughout the circuit diagrams of Figures 1 and 2, all ground connections will be considered as corresponding to a connection to battery mid-point.

The transmitter also comprises any known or 10 preferred form of transmitting distributor TD comprising the eight contact segments 33 to 40, inclusive. The rotary element of the distributor connects with the polarized sending relay 15, which in turn connects with any suitable radio transmitter RT which emits the radio wave in which the signal elements are defined in any well known manner. Each station having such radio transmitting apparatus RT also includes as a part of its equipment a suitable radio receiver RR, which will be described later in connection with Figure 2. It will be noted that the first 15 three contact fingers 21, 22 and 23 of the tape controlled contact fingers have permanent electrical connection with the first three distributor segments 33, 34, and 35, and that the last two contact fingers 24 and 25 of said group are operable to have connection with the next two distributor segments 36 and 37 through relay armatures 64 and 65, the latter performing controlling or coding functions which will be later described.

The apparatus for adding the three extra signal elements to make up the eight unit code comprises a bank of three supplementing relays 35 29, 30, and 31, it being noted that their respective armatures 26, 27, and 28 are connected with the last three segments 38, 39, and 40 of the transmitting distributor TD. These relays are of the polarized type in which each armature remains in its actuated position after the cessation of the actuating current impulse and until a current impulse of opposite polarity traverses the relay winding for actuating the armature to the other position, these armatures remaining in 40 rest positions (in engagement with their left hand contacts) when negative polarity is applied to the relay windings. When the armatures are in engagement with their left hand contacts they receive positive polarity and when they are 45 in engagement with their right hand contacts they receive negative polarity. The windings of said relays 29, 30, and 31 are connected with the timing contacts 8, 9, and 10, respectively, and also with the timing contacts 5, 6, and 7, 50 respectively. The timing contacts 1 to 20, inclusive, are all mounted on a common shaft V¹ for synchronous operation, these contacts only being shown diagrammatically in Figure 1 but actually having the varied timing intervals illustrated in Figure 4. The shaft V¹ has the same speed as the rotary member of the transmitting distributor TD. A second shaft V² associated with both the transmitter and receiver of each station operates the timing contacts a, b, c, d, e₁, e₂, and e₃ of the transmitter, and also the timing contact I of the receiver (see Figure 6). This second shaft V² is adapted to be started by the electromagnet ST of the receiver (Figure 2), as will be later described, and rotates at a speed 55 which is $\frac{1}{36}$ of the speed of the first mentioned shaft V¹. Three other shafts V³, V⁴, and V⁵ are also arranged to rotate timing contacts of the transmitter under the control of electromagnets associated with the receiver. Shaft V³ rotates 60 timing contacts A₁, B₁, and C₁, and is adapted

to be started by the electromagnet S^3 of the receiver; shaft V^4 rotates the timing contacts A_2 , B_2 , and C_2 of the transmitter, and is adapted to be started by the electromagnet S^4 of the receiver; and shaft V^5 rotates timing contacts A_3 , B_3 , and C_3 of the transmitter, and is adapted to be started by the electromagnet S^5 of the receiver. The timing intervals of the various contacts associated with these several shafts are illustrated in Figure 6.

Referring now to the manner in which the transformed signals (O and V of Figure 3) are formed, the apparatus for transforming the signals which have five equal elements into signals having five non-equal elements followed by three additional elements in the characteristic combinations illustrated at O or V comprises a pair of polarized relays 41 and 42 which are adapted to be energized whenever all of the contact fingers or feeling tongues 21-25, inclusive, occupy similar positions. The movement of all of said contact fingers 21-25 to similar positions causes these fingers to have potentials of equal polarity. If, then, shortly after the fixation of the five unit signal the bank of timing contacts 14 to 18, inclusive, are closed, it will be evident that a current of corresponding direction will flow through the polarized relays 41 and 42. This current will be of one polarity if all of the contact fingers 21-25 are in their raised positions, and will be of the opposite polarity if all of said contact fingers are in their lowered positions. Accordingly, this current will energize the relays 41 and 42 and cause either one or the other of the armatures 45 or 46 to move to circuit closing position, depending upon the polarity of the current to said relays. At the moment at which timing contacts 14-18 are closed, the timing contacts 3 and 4 are open (see Figure 4), so that the spacing and marking contacts associated with the contact fingers 21-25 are connected to the voltage source through resistances 43 and 44. It will thus be seen that the closure of timing contacts 14-18 does not result in a complete short circuit in the event that the contact fingers 21-25 do not all occupy similar positions. In such case, the transforming apparatus should not function, and to this end the relays 41 and 42 do not carry current at this time, inasmuch as the contacts 14 to 18, as well as contact 13, then have the potential of battery mid-point. When the relays 41 and 42 are energized they close holding or lock-up circuits through their armature contacts 45 and 46, such holding circuits being opened upon the opening of timing contact 13. Therefore it will be seen that until the opening of timing contact 13 the point 47 has a potential corresponding in polarity to that of the similarly positioned contact fingers 21 to 25. This voltage, whether of one polarity or the other, now energizes the relay 48, which attracts its armatures 49, 50, 51 and 52. The nature of the transformation resulting from this energization of the relay 48 will be first described in the situation where a five-space signal is being applied to the contact fingers 21 to 25, in which situation the contact fingers are all on their lower contacts in Figure 1, such corresponding to five successive circles according to the system of notation shown in Figure 3. After the armatures 49 and 50 have been attracted by the energization of the relay winding 48, contact finger 21 remains connected with positive (such being the spacing current or zeros of Figure 3); contact finger 22 is now connected

to negative through the new position of armature 50; contact finger 23 remains connected to positive; contact finger 24 is now connected to negative through the new position of armature 50; and contact finger 25 remains connected to positive. Thus, the first five elements of signal O of Figure 3 are formed. With reference to the last three elements of this signal formed through the supplementing relays 29, 30, and 31, these 10 three relays are energized at this time through timing contacts 5, 6, and 7. Thus, relay 30 is connected with negative through timing contact 6 and armatures 69 and 71; and relays 29 and 31 are connected with positive through timing contacts 5 and 7 and armatures 51 and 70. Such energization of the relays 29, 30, and 31 results in the relay armatures 26 and 28 having negative or marking voltage and the relay armature 27 having positive or spacing voltage, thus producing the last three signal elements shown in signal O. The converse situation of transforming a five marking unit signal (wherein all five contact fingers 21-25 are in their upper positions corresponding to five marking elements denoted X in Figure 3) into the eight unit signal V of Figure 3 will be apparent from the description of the preceding transformation. In this latter transformation, the energized position of the armature 49 reverses the polarities supplied to 20 the upper contacts associated with contact fingers 21, 23, and 24 in much the same manner that the armature 50 reversed the polarities of the lower contacts of contact fingers 22 and 24 in the preceding transformation. 25 It should be observed that when relay 48 is energized, its armature 52 interrupts the test conductor 32 so that this conductor and the relay 53 are rendered inactive. 30 Referring now to the manner in which the normal signals (I-IV of Figure 3) are formed, the three control relays 41, 42, and 48 remain at rest whenever a signal having four or less equal elements is applied to the contact fingers 21-25. The three signal supplementing relays 29, 30, and 31 return to rest position in engagement with their positive contacts when negative is applied to the relay windings over the circuits closed by the timing contacts 5, 6, and 7. Under such conditions, these latter relays thus add spaces (the signal impulses represented by the circles in Figure 3) to the five units of the original signal. In this manner, a signal having four marking units and one spacing unit is converted into the eight unit signal IV of Figure 3. In the case of 35 a signal in which the number of marking units is smaller than four, the polarized relay 53 is energized in a bridge connecting with the resistances 54-61 by way of the test conductor 32. This test conductor will not carry current when the eight unit signal is balanced, because such causes equal amounts of positive and negative currents to flow in the resistances 54-61. In order to effect the conversion of the different normal signals, the five unit signal is tested three times by the action of timing contacts 8, 9, and 10, which coact with timing contacts 11 and 12. If the signal is not balanced on the first test the first supplementing relay 29 is brought into the marking position (armature to the right) over 40 a control circuit through contact 62 of relay 53 and through timing contact 8. If at the second test the signal is not yet balanced, the second supplementing relay 30 is brought into marking position. Finally, if the signal should not yet be balanced at the third test, the third supple-

menting relay 31 is also moved to marking position. In this manner, the signals III, II, and I of Figure 3 are consecutively formed respectively from original signals having three, two, or one marking units.

In the above functioning of timing contacts 8, 9, 10, 11 and 12, it will be seen from Figure 4 that the contact 11 intermittently establishes a holding circuit for the relay 53, which holding circuit is closed concurrently with each closing of contact 12 and which carries over through each closed circuit interval of the successively operating contacts 8, 9, and 10.

Referring now to the manner in which the warning signals (VI-VIII of Figure 3) are formed, it will be seen that the signals O to V, inclusive, utilize all groupings or sequences of the three added elements except those shown in these last three signals VI, VII, and VIII. These last three are used for warning purposes, but it is necessary that they be completed by five preceding elements of such polarity that a balanced eight unit signal results. Three relays S⁶, S⁷, and S⁸, operating in conjunction with "blank" relay BL, serve to give these warning signals. An understanding of these functions will be facilitated by first considering the operation of said blank relay BL. The energization of this relay is under the control of timing contacts a, B₁, B₂, B₃, 19, and 20. Responding to the energization of said relay are armatures 63, 64, 65, 66, and 67. The actuation of armature 63 causes relay 48 to be energized, and this establishes the correct polarity of the first three elements and of the last three elements of the eight unit signal corresponding to signal O of Figure 3, such operation occurring independently of the position of the contact fingers 21-25. This will be apparent from the preceding description of the operation of relay 48, from which it will be recalled that the first three elements of the transformed eight unit signal were the same whether the contact fingers were in their upper positions or in their lower positions, as evidenced by signals O and V of Figure 3. With regard to the last three elements of the signal, the three supplementing relays 29, 30, and 31 produce marking, spacing and marking elements respectively (signal O) in the same manner that they produced this three element combination in the transforming operation previously described. With regard to the fourth and fifth elements, these are given their correct polarity by the armatures 64 and 65 of relay BL. Relay armature 66 establishes a holding or lock-up circuit for the winding of blank relay BL during the time that timing contact 19 is closed. The signal produced by the above operation is therefore a so-called "blank," i. e., the receiving printer is supplied with a five space signal, to which signal it does not respond at all. That is to say, the signal which is transmitted over the radio path is signal O (Figure 3), but after transformation at the receiving station into a five unit signal it takes the form of five spaces, to which the receiving printer does not respond. The armature 67 of relay BL at the transmitter interrupts the circuit of the starting relay or winding S, as otherwise, when a blank is given, a letter would be missed. It should be further observed that this blank signal is also given in the absence of a perforated strip in the transmitter, i. e., the signal then given is signal O of Figure 3. Inasmuch as this signal consists of successive reversals of spacing and marking elements it considerably facilitates the receiver adjustment.

As distinguished from "blank," the system uses, in known manner, the signal "letterblank" consisting of five markings (therefore signal V of Figure 3) and which is used to change from numbers to letters. On the radio path this signal is in the eight unit form indicated at V, but after transformation at the receiving station into a five unit signal it takes the form of five markings.

Referring again to the function of the signaling relays which cause the emission of warning signals, the first warning signal is given by the simultaneous energization of relays BL and S⁶. The energization of relay BL operates its armatures 63 to 67, inclusive, as above described, and the energization of relay S⁶ attracts its armatures 68 and 69. The actuation of armature 68 transmits negative polarity to the winding of supplementing relay 29, and the actuation of armature 69 transmits positive polarity to the winding of supplementing relay 30. Positive polarity is transmitted to the winding of supplementing relay 31 by reason of the energization of relay 48 through armature 63. Armatures 65 and 64 transmit negative and positive polarities to the distributor segments 36 and 37 respectively. As a result, warning signal VI of Figure 3 is emitted from the transmitter. At the receiver, this will indicate that the transmitter on its side has transmitted a signal which has been mutilated before reception, for which reason it has to be repeated. The manner in which the receiver influences its own transmitter will be hereinafter described. Meanwhile, it should be noted that after the transmission of the first warning signal from A to B, A transmits a second warning signal, this time by the simultaneous energization of relays BL and S⁷. Armatures 70 and 71 are thereby actuated, which transmits negative polarity to supplementing relay 29, positive polarity to supplementing relay 30, and negative polarity to supplementing relay 31. Armature 72 is also actuated, which transmits negative polarity to the distributor segment 37 for producing a marking element as the fifth signal element. Such actuation of the armatures of relays BL and S⁷ results in the emission of signal VII of Figure 3. This second warning signal from A now causes at receiver and transmitter B the repetition of as many signals as have been transmitted during the time between the emission of warning signals VI and VIII, as will be hereinafter described. After the transmission of the second warning signal, a third warning signal is emitted by A, such being effected by the simultaneous energization of relays BL and S⁸. The energization of the relay S⁸ causes actuation of the armatures 73 and 74. The actuation of armature 73, together with the actuation of the armatures which respond to relay BL, results in negative polarity being transmitted to the supplementing relay 29, negative polarity being transmitted to the supplementing relay 30, and positive polarity being transmitted to the supplementing relay 31. The actuation of armature 74 also transmits negative polarity to the distributor segment 37 in the same manner that armature 72 transmitted negative polarity to this segment when relay S⁷ was energized. In consequence, warning signal VIII is thereby emitted from the transmitter. The arrival of this signal at the receiver B results in the emission of as many signals from its transmitter as has been emitted between the sending of warning signals VII and VIII.

Referring now to the circuit diagram of the

receiver, illustrated in Figure 2, it will be noted that this apparatus comprises a multiplicity of timing contacts 91 to 110, inclusive, all mounted on a shaft V^6 . Said shaft V^6 has the same speed as the rotary member of the receiving distributor RD, and the timed relation of these several contacts is illustrated in Figure 5. The receiving apparatus also includes the timing contact I which is mounted on the shaft V^2 associated with the transmitting apparatus, as previously described. The receiving apparatus comprises the polarized receiving relay 76 which receives the signals from any suitable radio receiver RR, such radio apparatus being well known, and hence not being shown in detail. As previously described, each station having such radio receiving apparatus RR also includes as a part of its equipment a suitable radio transmitting apparatus RT, illustrated in Figure 1. The receiving relay 76 energizes the receiving distributor RD with different polarities corresponding to the positions consecutively occupied by the armature of the polarized sending relay 75. The receiving distributor RD is shown with sixteen contact segments, the first thirteen of which connect with the windings of the polarized relays 77 to 89, inclusive. The fourteenth, fifteenth, and sixteenth segments are connected back to the windings of relays 82, 83, and 84. The first eight relays 77 to 84, inclusive, are energized in conformity with a received eight unit signal. The last five relays 85 to 89, inclusive, together with the last three relays, 82, 83, and 84 of the first group of eight, serve for the reception of the next eight unit signal. The relays 77-89 are of the polarized type in which, after the cessation of current flow through the relay windings, the armatures remain in the positions last assumed. Thirty of the utilized thirty-five combinations of the eight unit code (excluding signals O, V, VI, VII, and VIII of Figure 3) are received in the following manner. Upon the arrival of one of these thirty combinations, the first five elements of the first-mentioned signal are received by the relays 77 to 81, and are directed to the printer without any modification. This is effected at suitable moments through timing contacts 94 to 98, and occurs for all signals except those in which the three element combination received on the last three relays 82, 83, and 84 of the first group corresponds to the last three elements of signals O, V, VI, VII, and VIII. When the signal terminates with the last three elements of the latter combinations, the armatures of relays 82, 83, and 84, and consequently the armatures 116-121 of relays 111, 112, and 113, are caused to occupy such positions that one of the relays 114, 115, S³, S⁴ or S⁵ is energized via circuit connections established through armatures 116-121. Relays 114 and 115 are energized by signals O and V. The energization of relay 114 actuates armatures 114', 122, and 123; and the energization of relay 115 actuates armatures 115', 124, and 125. Timing contacts 104 and 105 are interposed in series respectively with the windings of relays 114 and 115; and timing contacts 106 and 107 control holding circuits through the armatures 114' and 115' respectively for keeping each of the relays 114 and 115 energized for a predetermined time interval. Relay S³ operates, when energized by signal VI, to start the shaft V^3 on which are mounted the timing contacts A₁, B₁, and C₁ of the transmitter of that same station; relay S⁴ operates, when energized by signal VII, to start shaft V^4 on which are mounted the

timing contacts A₂, B₂, and C₂ of said transmitter; and relay S⁵ operates, when energized by signal VIII, to start shaft V^5 on which are mounted the timing contacts A₃, B₃, and C₃ of said transmitter. The functions performed upon the starting of these shafts will be described later. The relay 144, which has its winding connected in series with the relays S³, S⁴, and S⁵, is arranged to interrupt the printer starting circuit through its armature 144'. The relays 82-84 and 111-113 are now at liberty to be controlled anew in accordance with the next signal, such control taking effect when the first five elements of the next signal have arrived to control relays 85-89. The armatures of said latter relays are connected to the printer at suitable moments through timing contacts 99-103.

Relays 114 and 115 are energized on the arrival of a signal corresponding to O or on the arrival of a signal corresponding to V (Figure 3). Timing contacts 104 and 105 have such timed sequence as to cause the aforementioned signal which first arrives to energize relay 114, and to cause the aforementioned signal which next arrives to energize relay 115, this distinction applying in case of arrival of signal O as well as of signal V. The energization of relay 114, for example, causes its armatures 122 and 123 to be brought into engagement with their right hand contacts, whereby the upper and lower contacts of the first four relays 77-80 have the same polarity impressed thereon as is impressed on the armature of the fifth relay 81, such connection being established through conductor 123'. That is to say, the fifth element of signal O or the fifth element of signal V will determine the polarities or voltages impressed on these upper and lower contacts of said first four relays. In consequence, the first five elements of the signal undergo a retransformation (as will appear from Figure 3) opposite to the transformation that they received in the transmitter. In corresponding manner, the other relay 115 takes care of the signal which is next received by imposing on the upper and lower contacts of relays 85-88 the same polarity as is imposed on the armature of relay 89, such connection being established through conductor 125'. Relays S³, S⁴, and S⁵ are energized when the transmitter of the other station emits warning signals VI, VII, and VIII (Figure 3), such energization being through circuit connections established by way of relay armatures 116-121 in consequence of the three element combinations at the ends of these warning signals, which elements are received by the relays 82, 83, and 84.

The apparatus at the receiver for the detection of mutilations in the signals operates as follows: The said signal which arrives first energizes relays 77-84; the armatures of these relays are then connected in circuit with relay ST by way of timing contacts 92 and 93 through the resistors 126-133. The upper and lower contacts of relays 77-89 are connected either to marking voltage (negative battery) or to ground (battery mid-point), and, accordingly, the other extremity of the winding of relay ST is connected to a point 139 which has a potential equal to half the said voltage. If the signal which has arrived contains equal numbers of positive and negative elements, the relay ST will not be energized. This is because four of the relays 77-89 have transmitted one polarity of current flow through timing contacts 92, 93 to the relay ST, and four other relays of this same group 77-89

have transmitted the opposite polarity of current flow through said timing contacts 92, 93 to said relay ST. Hence, the two polarities balance each other out and there is no energization of relay ST. In any other instance, i. e., whenever the signal is a mutilated one, relay ST is momentarily energized because an unbalanced condition exists either by reason of a greater number of positive elements than negative elements or a greater number of negative elements than positive elements. This closes a circuit through armature 140 which energizes relay ST². The latter relay actuates armatures 141, 142, and 143, the first of which completes a holding circuit for said relay through timing contact 110. The actuation of armature 142 interrupts a circuit connection to battery mid-point which in turn prevents energization of relays S³, S⁴, and S⁵ whenever the reception has been mutilated. The actuation of armature 143 interrupts the printer start circuit so that the mutilated letter is not printed at receiver B. The energization of the relay ST starts the shaft V² for transmitting warning signals from transmitter B, in a manner which will now be described.

The shaft V², started by the relay ST of receiver B, rotates at $\frac{1}{36}$ of the speed of the transmitter shaft V¹, and said shaft V² controls timing contacts a-d, e¹, e², and e³ of the transmitter B, and also controls timing contact I of the receiver B, which remains open during thirty-six revolutions of the transmitter shaft V¹, so that the starting of the printer is prevented during this period of time required for transmitting the warning signals VI-VIII from the transmitter B, added to the time required, in the most unfavorable case, for station A to react to these signals. This most unfavorable case would occur when warning signals VI and VII have not been received without mutilation, and only warning signal VIII has caused the transmitter A to be set back. In station B, the closing of timing contacts a and b (Figure 1) causes the energization of relays BL and S⁶, whereby warning signal VI is transmitted. Six revolutions later timing contacts a and c are closed, thus energizing relays BL and S⁷, causing warning signal VII to be transmitted. On the sixth revolution of said shaft after signal VII has been transmitted, contacts a and d are closed for energizing relays BL and S⁸ to cause the emission of warning signal VIII.

Timing contacts e₁, e₂, and e₃ of station B exercise a necessary control function when, during the described operation of the shaft V² of station B, the transmitter A transmits warning signals to the receiver B for the purpose of indicating to that station that its warning signals transmitted over the path BA have been mutilated. In this situation the warning signals transmitted back from station A cause timing contacts A₁, B₁, and C₁, or A₂, B₂ and C₂, or A₃, B₃, and C₃ of transmitter B to become operative. The nature of the above mentioned control function exercised by the timing contacts e₁, e₂ and e₃ of station B will be best understood after first considering the action of warning signals VI-VIII on station A, which will now be described.

Warning signals VI-VIII, transmitted from B, will arrive at A after the transmitting shaft V¹ of A has rotated one or more revolutions beyond the revolution which emitted the message signal which was mutilated in its transit from A to B. The telegraph transmitter of station A should therefore be set back by several signals; in the particular embodiment herein disclosed it is set

back by five signals under normal operating conditions. However, if the transmitter A has meanwhile been engaged in transmitting a warning signal to the receiver B, this number should be made smaller by one, because during the emission of said warning signal the perforated strip has not been advanced. For the purpose of interrupting the transmitter start circuit (station A), the armature 67 of relay BL is interposed in series between the timing contact 2 and the winding of the transmitter start device S. When warning signal VI arrives at receiver A it causes relay S³ to be energized, thereby causing shaft V³ to be started. This shaft likewise turns at a speed of $\frac{1}{36}$ of the transmitter shaft V¹, and rotates timing contacts A₁, B₁, and C₁. Timing contact A₁ energizes the back step relay T of the transmitter (station A) for six revolutions of the transmitter shaft V¹. Timing contact B₁ energizes relay BL for twenty-nine revolutions of the transmitter shaft V¹, so that transmitter A transmits the aforementioned blanks during that time. Attention is called to the fact that the telegraph transmitter (station A) will only start when relay S is energized, as well as when stepping backwardly when relay T is energized. The start circuit of relay S, which was interrupted at armature 67 during the emission of blanks, will therefore have to be closed again during the six back steps, such closure of this circuit being effected at timing contact C₁, which establishes a shunt around armature 67. It should be noted at this point that the closure of contact C₁, in order to be effective, also requires the closure of contact e₁, which will be referred to later. The emission of blanks (from station A) during the twenty-three subsequent steps is necessary because at the sender B the received mutilated signal has resulted in further operations, such as the emission of signals VII and VIII, and during which time station B should not accept signals. The possibility that station A will not react before signal VIII arrives should also be taken into consideration; in this case the inactive period is required for enabling the transmitter to return to the correct letter.

Start relays S³, S⁴, and S⁵ are so mechanically interlocked that when station A has reacted to signal VI, the signals VII and VIII emitted by station B will not be effective to again initiate a starting operation at station A.

As the telegraph transmitter was set back by six steps, whereas the transmission delay only required it to be set back five steps, the receiver B must not print the first signal to arrive after resumption of the transmission from station A. To prevent the printing of this first signal, timing contact I remains open for one turn longer.

In the above mentioned instance where the telegraph transmitter should be set back one step less, i. e., in the event that there has been a reaction to signal VI, this function is performed by rotary contact e₁ which is connected in series with rotary contact C₁, and to which reference has already been made.

In the event that station A does not react to signal VI, it is almost a certainty that it will react to one or the other of the two succeeding signals VII and VIII. The operation of the apparatus under the control of the latter signals corresponds to that under the control of signal VI, timing contacts A₂, B₂, and C₂ being set into operation by signal VII, and timing contacts A₃, B₃, and C₃ being set into operation by signal VIII, in the same manner that timing contacts A₁, B₁, and

C_1 were set into operation by signal VI. The delays and the number of back steps will, of course, differ in the case of each of these three signals, as will be apparent from Figure 6. If station A should not react to a single one of these three warning signals, receiver B will miss some letters. The possibility of such an occurrence is, however, exceedingly small on normal circuits. In any case, the system prevents the printing of mutilated letters, and the missing of a great number of letters cannot pass unnoticed.

The synchronism of the transmitter shaft V^1 at station A and receiver shaft V^6 at station B, as well as that of transmitter shaft V^1 at station B and receiver shaft V^6 of station A, is maintained in known manner.

In the foregoing description I have described a sequence of operations wherein the message signals are transmitted from station A for reception at station B, but it will be understood that the message signals can, of course, originate at station B for reception at station A, in which case this same sequence of operations occurs in reversed relation with respect to the two stations.

While I have illustrated and described what I regard to be the preferred embodiment of my invention, nevertheless it will be understood that such is merely exemplary and that numerous modifications and rearrangements may be made therein without departing from the essence of the invention.

I claim:

1. In an electrical system of communication, the method of signaling which comprises transmitting code combination signals each composed of a predetermined number of elements having different electrical values so chosen that they bear a constant relationship to each other in each transmitted combination, and balancing the different signal elements received at the receiving apparatus against each other so as to differentiate between true signals which have this constant relationship and other signals which have been mutilated.

2. In printing telegraphy, the method of signaling which comprises transmitting code combination signals each composed of so-called marking and spacing elements so coded as to be in a constant numerical ratio to each other in each letter or numeral transmitted, balancing the marking and spacing elements received at the receiving apparatus against each other so as to differentiate between signals in which this constant numerical ratio is present and any mutilated signals or groups of extraneous impulses in which this constant numerical ratio is not present, and then printing at the receiving apparatus only those signals having such constant numerical ratio.

3. In radio telegraphy, the method of signaling which comprises formulating signals in a code combination characterized by a predetermined number of positive and negative impulses in an equal ratio in each signal, transmitting said signals by radio from a radio transmitting station in such manner that said positive and negative impulses produce an equal ratio of distinctive components in each radio signal, receiving said signals at a radio receiving station, causing said radio signal components to establish corresponding positive and negative impulses at the receiving station, and balancing said positive and negative impulses against each other at the receiving station so as to differentiate between true signals

and signals which have been mutilated by atmospheric conditions.

4. In printing telegraphy, the method of signaling which comprises converting signals from a conventional five unit code into signals of a second code by the addition of signal elements in such manner that the components of each converted signal are maintained in a constant numerical ratio, transmitting such signals in this second code to a receiving station, utilizing this constant ratio characteristic at the receiving station to differentiate between mutilated and unmutilated signals, and converting the unmutilated signals back into said conventional five unit code for printing.

5. In radio telegraphy, the method of signaling which comprises transmitting code signals from a radio transmitting station on a single radio channel, said channel being composed of different classes of components maintained in a fixed ratio in each signal, receiving said signals at a radio receiving station, and testing the signals received at the receiving station by a differentiating operation wherein signal components of one class act in opposition to signal components of another class to determine the presence or absence of said fixed ratio.

6. In an electrical signaling system, the combination of transmitting apparatus operative to transmit code combination signals composed of elements having different electrical values so chosen as to bear a constant numerical relationship to each other in each letter or numeral transmitted and receiving apparatus adapted to receive the signals transmitted from said transmitting apparatus and also receiving mutilated signals and extraneous impulses, said receiving apparatus being operative to differentiate between signals which have this constant numerical relationship and those which do not, and comprising means for automatically transmitting a special signal back to said transmitter upon receiving a mutilated signal not having this constant numerical relationship.

7. In a telegraph system, the combination of transmitting apparatus operative to transmit code combination signals on a single channel each composed of a fixed number of elements having different electrical values so chosen in a constant numerical ratio that the resultant signal of each letter has a predetermined electrical value, and receiving apparatus adapted to receive the signals transmitted from said transmitting apparatus and operative to differentiate between signals having such predetermined electrical value and any mutilated signals or extraneous impulses not having this predetermined electrical value, said receiving apparatus comprising means for automatically transmitting a special signal back to said transmitting apparatus upon the reception of a mutilated signal.

8. In a radio telegraph system, the combination of a radio transmitter comprising means for establishing signals characterized by a fixed ratio of positive and negative impulses in each signal, means for transmitting said signals by radio over a single radio channel in such a manner that said positive and negative impulses produce the same fixed ratio of different components in each radio signal corresponding to said positive and negative impulses, and a radio receiver receiving said signals from said radio transmitter comprising means for converting such components of the radio signals back into corresponding positive and negative impulses, means opera-

tive to test the converted signals for said fixed ratio of positive and negative impulses, and means for automatically transmitting a special radio signal from said radio receiver to said radio transmitter upon the reception at said receiver of a mutilated signal not having such fixed ratio of positive and negative impulses.

9. In an electrical system of communication, the combination of means for converting signals from a first code into signals of a second code 10 in which the components of each signal are maintained in a constant numerical ratio, means for transmitting such latter signals, and receiving apparatus comprising means for receiving and testing said latter signals to determine if their components are in said constant ratio, and means for converting the tested signals back into said first code.

10. In a radio telegraph system, the combination of means for converting signals from a conventional five unit code into signals of an eight unit code in which each signal is composed of a predetermined relation of positive and negative impulses having a total potential of zero, a radio transmitter for transmitting said latter signals 15 over a single radio channel, a radio receiver for receiving said latter signals comprising means for testing the received signals for said zero potential to determine whether the signals have been mutilated in transmission, and means for converting the unmutilated signals back into said conventional five unit code for operating a printer.

11. In electric signaling apparatus for converting signals from a first code into a second code in which a fixed ratio of electrical values is maintained in each letter transmitted, the combination of a first group of conductors adapted to have different current values impressed thereon corresponding to said letters as coded in said first code, a second group of conductors adapted to have different current values impressed thereon corresponding to additional signal elements employed in converting the letter signals from the first code to the second code, supplementing relays for governing the current values impressed on the conductors of said second group, and testing relay apparatus responding to the current values impressed on said first group of conductors during the transmission of each letter for controlling the operation of said supplementing relays.

12. In a transmitter for a radio telegraph system, the combination of a transmitting distributor comprising a first group of contacts and a second group of contacts, apparatus responsive to a perforated signal tape for impressing different polarities on said first group of contacts in code relation for each character transmitted, polarized relays for impressing different polarities on said second group of contacts, a bank of resistors connected with the contacts of both groups, and means including a relay responsive to the current flow through said bank of resistors corresponding to the particular character to be transmitted for causing the operation of said polarized relays in sequence until the polarities impressed on both groups of contacts are in balanced relation.

13. In a transmitter for a radio telegraph system, the combination of a transmitting distributor comprising a group of contacts, apparatus responsive to a perforated signal tape for impressing different polarities on said distributor contacts in code relation corresponding to the different letter characters to be transmitted, relay ap-

paratus adapted to be actuated in the event that the same polarity is impressed on all contacts of said group in a single letter signal, and means responsive to said relay apparatus for transforming such signal by changing the polarity impressed on one or more of said distributor contacts.

14. In a radio telegraph system, the combination of a radio transmitter for transmitting signals each composed of a predetermined relation of positive and negative impulses the total electrical value of which is zero, a radio receiver for receiving said signals comprising integrating means for testing the total electrical value of the impulses in the received signals, and a printer adapted to respond to said signals, said integrating means governing the operation of said printer.

15. In a radio telegraph system, the combination of a radio transmitter comprising means for transmitting signals on a single radio channel each composed of precalculated significant and supplementary impulses the total electrical value of which is zero, said transmitter comprising a transmitting distributor through which said impulses are impressed on the radio channel in timed sequence, a radio receiver adapted to receive such signals from said radio transmitter comprising a receiving distributor operated synchronously with said transmitting distributor, integrating means receiving the signal impulses from said receiving distributor and comprising a bank of resistors through which the total electrical value of all impulses in each signal is tested, a printer adapted to respond to the significant impulses of each signal, and printer control means comprising a relay responsive to the current flow through said bank of resistors for governing the operation of said printer.

16. In a radio telegraph system, the combination of a radio transmitter comprising means for transmitting signals on a single radio channel each composed of several predetermined impulses the total electrical value of which is zero, said transmitter comprising a transmitting distributor through which said impulses are projected on the radio channel in timed sequence, a radio receiver adapted to receive such signals from said radio transmitter comprising a receiving distributor operated synchronously with said transmitting distributor, integrating means receiving the signal impulses from said receiving distributor and comprising a bank of resistors through which the total electrical value of all impulses in each signal is tested, a printer adapted to respond to said signal, printer control means comprising a relay responsive to the current flow through said bank of resistors for governing the operation of said printer, means operative to transmit a warning signal from said radio receiver back to said radio transmitter, and means responsive to said printer control means for causing said last named means to operate.

17. In a telegraph system, the combination of a transmitter including a distributor, a receiver including a distributor operating synchronously with said transmitting distributor, said receiver comprising a first group of polarized relays and a second group of polarized relays each having their windings connected with separate groups of contacts of said distributor, the armatures of said first group of relays adapted to engage in one position with one set of relay contacts normally having one potential impressed thereon and adapted to engage in their other position with another set of relay contacts normally having an-

other potential effective thereon, a printer adapted to receive signal impulses from said latter armatures, and means responsive to signal impulses received on said second group of relays for varying the potentials effective on the relay contacts of the first group of relays.

18. In a telegraph system, the combination of a first signal station including means for transmitting signals each having a predetermined total electrical value, a second signal station including a transmitter and a receiver, said receiver comprising integrating means for testing the total electrical value of the signals received from said first station, a rotary shaft, means responsive to said integrating means for controlling said rotary shaft, and means responsive to said rotary shaft for causing said transmitter of said second station to transmit warning signals to said first station.

19. In a telegraph system, the combination of a signal station including a transmitter and a receiver, said transmitter comprising means for feeding a perforated tape, and contact members responding to the perforations in the tape, said receiver comprising a plurality of relays adapted to respond to warning signals transmitted from another station, a plurality of rotary shafts separately controlled by said relays, and means responsive to said rotary shafts for setting back said paper tape and for causing said transmitter to transmit blank signals.

20. In a radio telegraph system, the combination of two stations each including a radio transmitter and a radio receiver, the radio transmitter of each station comprising means for transmitting signals each composed of elements having different electrical values so chosen that they bear a constant relationship to each other in each transmitted signal, the radio receiver of each station comprising a bank of polarized relays adapted to receive the different elements of each signal transmitted from the other station, integrating means actuated by the signal elements from said bank of polarized relays and comprising a bank of resistors through which each signal is tested to determine whether the elements thereof bear the aforesaid constant relationship to each other or whether the signal has been mutilated in transmission, a printer, rotary contact means for controlling the admission of the unmutilated signals from said polarized relays to said printer, and means responsive to said integrating means in the event of the reception of a mutilated signal for interrupting the operation of said printer and for causing the associated transmitter to transmit warning signals.

21. In an electrical system of communication, the combination of transmitting apparatus comprising means for transmitting code combination signals on a single channel each of which signals is composed of two kinds of impulses having electrical values so chosen that they bear a constant relationship to each other, and apparatus for receiving said signals comprising means mutually responsive to said two kinds of impulses for distinguishing between said code combination signals which have this constant relationship and other mutilated signals which do not.

22. In an electrical system of communication, the combination of transmitting apparatus for transmitting code combination signals on a single channel each of which signals is composed of groups of positive and negative impulses, a plurality of said groups being coded so that each designates a separate letter of the alphabet, said

transmitting apparatus including means for causing the positive and negative impulses to be in a constant ratio to each other in each of these groups, and receiving apparatus for receiving said signals comprising means jointly responsive to the number of said positive impulses and to the number of said negative impulses in each signal for differentiating between code combination signals which have this constant ratio and other mutilated signals which do not.

23. In an electrical system of communication, the method of signaling which comprises transmitting code combination signals from a transmitting station over a single channel, a plurality of said signals being composed of two kinds of elements having different electrical values so coded as to bear a constant relationship to each other in each of said code combination signals, receiving said signals at a receiving station, distinguishing at said receiving station between coded signals having this constant relationship and mutilated signals which do not, and automatically transmitting a warning signal from said receiving station back to said transmitting station upon the reception of such mutilated signal at said receiving station.

24. In an electrical system of communication, the combination of transmitting apparatus comprising means for transmitting code combination signals, each of which signals is composed of a plurality of kinds of impulses which bear a balanced numerical relationship to each other in each of said code combination signals, and apparatus for receiving said signals comprising means jointly responsive to the number of impulses of one kind and to the number of impulses of another kind for distinguishing between said code combination signals which have this balanced relationship and other mutilated signals which do not.

25. In an electrical system of communication, the method of signaling which comprises transmitting code signals each composed of four positive elements and four negative elements, and subjecting the signals received at the receiving station to a differentiating operation wherein the positive elements act in opposition to said negative elements to distinguish between true signals which have this relationship of four positive elements and four negative elements, and other mutilated signals which do not.

26. In an electrical system of communication, the method of signaling which comprises transmitting code combination signals each composed of eight elements made up of so-called marking and spacing elements so coded as to be in a constant numerical ratio to each other in each series of eight, and sensing the marking elements and also the spacing elements in each signal received at the receiving apparatus so as to distinguish between true signals which have this constant numerical ratio of marking and spacing elements, and other mutilated signals which do not.

27. In an electrical system of communication, the combination of transmitting apparatus comprising means for transmitting code combination signals each of which signals is composed of a series of eight elements made up of different kinds of elements which bear a constant relationship to each other in each series of eight, and apparatus for receiving said signals comprising relay means jointly responsive to said different kinds of elements in each series of eight for distinguishing between said code combination signals.

nals which have this constant relationship and other mutilated signals which do not.

28. In an electrical system of communication, the method of signaling which comprises transmitting code signals each composed of a predetermined number of positive elements and a predetermined number of negative elements, and testing the code signals received at the receiving station including sensing the number of positive elements and sensing the number of negative elements in each signal to distinguish between true code signals and mutilated signals.

29. In an electrical system of communication, the combination of transmitting apparatus comprising means for transmitting code combination signals, each of which signals is composed of a predetermined number of marking elements and a predetermined number of spacing elements, and receiving apparatus for receiving said signals comprising a plurality of relays operative to sense the number of marking elements and to sense the number of spacing elements in each received signal, and relay means operative to effect a relative valuation between the sensing established by

the relays responding to the marking elements and the sensing established by the relays responding to the spacing elements, whereby to distinguish between true code combination signals and mutilated signals.

30. In an electrical system of communication, the combination of radio transmitting apparatus comprising means for transmitting code combination signals over a radio channel, each of which signals is composed of a predetermined number of marking elements and a predetermined number of spacing elements which bear a constant relationship to each other in each transmitted signal, and radio receiving apparatus for receiving said signals comprising a plurality of polarized relays operative to sense the number of marking elements and to sense the number of spacing elements in each received signal, and relay means differentially responsive to the positions of said polarized relays for distinguishing between true code combination signals which have the aforesaid constant relationship, and mutilated signals which do not.

HENDRIK C. A. VAN DUUREN.
